COMPENSATOR FOR HOISTING APPARATUS

Otto E. Uecker, Milwaukee, Wis., assignor to
 A. O. Smith Corporation, Milwaukee, Wis., a
 corporation of New York

Application July 18, 1932, Serial No. 623,178
 Renewed June 20, 1934

15 Claims. (Cl. 91—18)

The invention relates generally to compensating apparatus for adjusting machine parts that are utilized to perform working operations in different temperatures.

5 The object of the invention is to provide for compensating for changes in size of the parts of apparatus utilized for performing work operations in atmospheres at different temperatures.

It is also an object of the invention to provide 10 compensating apparatus for machine parts used in different temperatures that may be readily adjusted to meet predetermined conditions.

For a fuller understanding of the nature and 15 objects of the invention, reference should be had to the following detailed description taken in conjunction with the accompanying drawings, in which:

Figure 1 is a view partly in section and partly 20 in side elevation of hoisting apparatus showing parts which, during operation, are exposed to different temperatures;

Fig. 2 is a view in side elevation of a portion of 25 the hoisting apparatus showing a compensating device constructed in accordance with my invention applied thereto for adjusting parts of the hoisting apparatus;

Fig. 3 is a view in side elevation of the carriage 30 of the hoisting apparatus in a lower position than in Fig. 2 showing the electrical circuits interrupted;

Fig. 4 is a view in front elevation of a portion 35 of the hoisting apparatus shown in Fig. 2 illustrating the relation of the members of the structure;

Fig. 5 is a view in side elevation of a switch 40 comprising a part of the compensating apparatus showing the manner in which it is mounted;

Fig. 6 is a view in side elevation showing the 45 adjusting means provided for my compensating apparatus; and

Fig. 7 is a circuit diagram of the controlling system for my compensating apparatus.

In the process of enameling pipe and other 45 heavy articles, it is necessary to provide hoisting apparatus and conveyors for moving the articles through the spraying apparatus, furnaces, and treating chambers. The temperatures of the atmospheres in the spraying booth, furnace, and spaces in-between differ greatly. The pipe before it enters the furnace is subjected to atmospheric temperatures, while in the furnace the temperatures may be as high as 1800° or 1900° F.

The hoisting and conveying apparatus utilized 50 for handling the pipe is also subjected to different temperatures and will change in size. In this

particular enameling apparatus, the hoisting mechanism or elevators and their hangers require compensating devices to adjust them when they change in size as a result of the temperatures. If compensating apparatus is not provided, the elevators would not always transfer the pipe to the proper level for delivery to the conveyor system.

Referring now to the drawings and Fig. 1 in particular, 10 designates generally a suitable hoisting apparatus or elevator for lowering or raising a pipe 9 from a furnace such as 11 or bath 12. The furnace is usually provided for fusing the enamel while the bath is utilized for quenching the enameled pipe.

15 The hoisting apparatus or elevator 10 comprises a plurality of endless chains 13 which may be driven in any suitable manner, such as by a motor not shown, a car 14 disposed to move in guide rails 15, shown best in Fig. 2, and a plurality of hangers 16. The car 14 is actuated by the chains 13. The hangers 16 are long enough to permit the lowering of the pipe through the furnace into the bath 12.

In lowering the pipe through the furnace, the 20 hangers 16 are exposed to the furnace heat and they change considerably in temperature as they are moved into and out of the furnace. If compensating means were not provided, these rods would not always return the pipe 9 and truck 8 25 to the same level and as a result the trucks would not register with the rails 19 of the conveyor system. The conveyor system has three different horizontal conveyor tracks, one above another, as illustrated in Fig. 1, the center track 19 being 30 adapted to convey the pipe 9 through the furnace 11, the upper track 19' being adapted to convey the pipe 9 to and away from the treating apparatus, and the lower track 19'' being adapted 35 to convey the pipe 9 through the bath 12.

40 Referring now to Figs. 2 and 3, the hangers 16 which depend from the car 14 comprise a short rod 17 journaled in a bracket 18 carried by the car 14 and a longer rod 17' connected to the shorter rod by means of a threaded buckle 20. 45 The insertion of the threaded buckle between the two rods provides means for adjusting one relative to the other. As illustrated, the buckle 20 is fixed with relation to the rod 17 and when rotated in one direction it will decrease the over-all length 50 of the hanger, while when rotated in the opposite direction it will increase the length of the hanger. The long rod 17' is disposed to slide in guides 21 mounted on the elevator car and to prevent it from rotating, when the rod 17 is rotated, a spline 55

22 is provided. The spline may be of any ordinary type well known in the art.

The hangers 16 are provided at their lower ends with crossheads 23 for carrying the trucks 8. In order to facilitate the transfer of the trucks 8 to and from the hangers 16, oppositely disposed crossheads 23 are provided with a pair of short rail sections 24. When the hangers are of the proper length, the rails carried thereby will register with the rails of the conveyor system when the elevator cars are actuated to the different predetermined levels.

The trucks 8 may be retained in position with the rail sections 24 in any suitable manner. A simple method of retaining them centrally located on the rail sections 24 is to provide depressions in the rail sections for the wheels of the truck. These depressions do not need to be very deep since a heavy weight is usually suspended from the trucks.

In order to measure the length of the hanger 16 when it is being raised from the furnace to receive or deliver a truck and pipe from or to the rails 19 of the conveyor system, a measuring stick or bar 25 is provided. This measuring stick is preferably made from such metal as invar, which has a very small coefficient of expansion, so that its changes in length as a result of the temperature range to which it is subjected are negligible. This measuring stick is supported on the elevator guide rails 15 and does not enter the furnace. As a result, the temperature range to which it is subjected is small.

The measuring stick is supported in sleeve brackets 26 which are carried by the guide rails 15 and may reciprocate in these sleeves. The downward movement of the measuring stick 25 is limited by a collar 27 fixed thereto and disposed to seat on the upper sleeve bracket 26. In the installation of the structure made, the movement of the measuring stick was limited to about four feet.

On the lower end of the measuring stick, an inwardly extending finger 28 is provided which is disposed to be engaged by an outwardly extending finger 29 provided on the hanger 16. Therefore when the hanger is drawn upwardly out of the furnace, the finger 29 will engage the finger 28 provided on the measuring stick and raise it.

Therefore when the hanger 16 is withdrawn from the furnace to the point where it picks up the measuring stick 25, the two stand in parallel and fixed relation to one another. If the hanger has been elongated or shortened as a result of a change in temperature, the difference in length between it and the measuring stick may be utilized for initiating the operation of some suitable mechanism for rotating the upper section 17 of the hanger and the buckle 20 to change its overall length.

In order to operate the buckle 20, a motor 30 is mounted on the elevator car 14 and connected to the upper section 17 of the hanger 16 through a train of gears 31. Therefore by operating the motor in the desired direction, the length of the hanger may be increased or decreased.

Referring now to Figs. 5 and 6, a switch shown generally at 32 is mounted on the measuring stick 25 for controlling the direction of rotation of the motor 30. As illustrated, the switch comprises two upper contact fingers 33 and two lower contact fingers 34 disposed in fixed relation on the measuring stick 25. A switch arm 35 is pivotally mounted at 36 on a

frame carried by the measuring stick and is provided with a bridging member 37 disposed to bridge either pair of contact fingers depending on the direction in which the switch arm is actuated. As illustrated, a spring 38 is disposed to bias the left end of the arm 35 downwardly projecting the bridging plate 37 into engagement with the contact fingers 33. The switch arm 35 extends through a slot 39 provided in the measuring stick 25. This guides the switch arm 35 and gives rigidity to the whole switch structure.

As illustrated in Fig. 5 a cam disk 40 is mounted on the elevator car. In this instance a bracket 41 is attached to the car frame at 42 in any suitable manner and has a threaded opening for receiving a post 43. The cam disk 40 is rotatably mounted at the upper end of the post 43. A spring 44 biases the cam disk 40 against the post and retains it in any position in which it may be set.

The cam disk is provided with eight faces at different distances from its pivot point 45, which permits eight adjustments. The cam disk 40 is disposed to engage the switch arm 35 and cooperate with the measuring stick 25 in effecting switching operations.

In order to supply current to the motor 30, a plurality of shoes 46 are mounted on structural columns adjacent the guide rails 15 at predetermined positions to engage the conductor bars 47 mounted on the elevator carriage 14. The conductor bars 47 are short and only engage the shoes throughout the upper portion of the movement of the elevator car.

In order to prevent the making and breaking of live circuits at the contact fingers 33 and 34 or shoes 46, a control switch 48 is mounted on one of the guide rails 15. When switch 48 is opened all the circuits are deenergized.

The control switch 48, as best shown in Fig. 7, comprises a bell crank and contact member for bridging a plurality of contact fingers. In order to actuate the switch 48 when the elevator is moving upwardly, a shoe 49 is mounted thereon to engage the outwardly extending switch arm near the upper limit of travel of the elevator. The shoe 49 is slightly shorter than the bars 47 so that the bars engage their respective shoes 46 in advance to the closing of control switch 48.

A reversing switch 50 for controlling the direction of rotation of the motor 30 is also mounted on a structural column of the building adjacent the guide rails 15 in a predetermined position. The reversing switch is of any usual type and its operation will be described in detail in connection with the circuit diagram illustrated in Fig. 7.

From the foregoing it will be evident that the motor is the only part of the compensating mechanism carried by the elevator car. The measuring stick 25 and the relay switch 32 thereon are disposed to move about four feet. The latter is electrically connected to the reversing switch 50, which is disposed in a fixed position, by flexible conductors 56 and 57 disposed therebetween.

Assuming now that the fusing of the enamel on the pipe 9 has been completed in the furnace 11 and that the pipe is being lowered into the bath 12, the hangers 16 are then lowered through the furnace and are exposed to the furnace temperature. The heating of the hanger 16 effects an elongation of the rods, particularly the rod 17. When the elevator car is moved upwardly, the 75

hangers will not bring the rail sections 24 into register with the rail sections 19 so that another truck 8 may be transferred thereto.

As the elevator car is moved upwardly, the finger 29 engages the finger 28 of the measuring stick and carries it upwardly. About the same time that the measuring stick is picked up by the hanger 16, the cam 40 carried by the elevator car engages the switch arm 35. Since the hanger has increased in length, it is longer than the measuring stick 25 and the switch arm 35 is actuated clockwise about its pivot point 36 projecting the bridging plate 37 into engagement with the contact fingers 34. The operation of the switch arm 35 is against the biasing force of the spring 38. As the elevator car progresses upwardly carrying with it the hanger, measuring stick, and switch 32, the conductor bars 47 engage the shoes 46. The switch 48 is then operated, closing the line switch 51 and the motor 39 is started. The direction in which the motor rotates is predetermined and connections made so that the buckle 20 is turned in the proper direction to shorten the hanger 16. As the hanger is shortened, the switch 32 is carried upwardly until the motor circuit is interrupted.

Referring now to Fig. 7, when the line switch 51 is closed, a circuit is established which extends from the power source 52, through conductor 53, line switch 54, conductor 54, the actuating coil of lower switch 55 of the reversing switch 50, flexible conductor 56, contact fingers 34 bridged by the plate 37, flexible conductor 57, and conductor 58, back to the power source. The switch 55 is actuated and establishes an armature circuit for the motor which may be traced from the energized conductor 54, through the upper pole of switch 55, conductor 59, one of the shoes 46, to a conductor bar 47, through the armature of the motor 39, back through another conductor bar 47, shoe 46, conductor 60, and the lower pole of the switch 55 to the negatively energized conductor 58.

When the conductor bars 47 are in contact with the shoes 46, the field of the motor 39 is connected directly across the power source 52. In this instance the field of the motor 39 is not reversed in order to reverse the rotation of the armature, but instead provision is made for reversing the armature current. This results in more positive stopping of the motor when the motor circuit is interrupted.

When the motor is started, it turns the buckle 20 and raises the rod 17 of the hanger reducing the over-all length of the latter. As the rod 17 is moved upwardly, it carries with it the measuring stick 25. As the switch 32 is raised with the measuring stick, the switch arm swings into its neutral position interrupting the motor circuit. If the hanger is too short when the elevator car moves upwardly, the cam 40 when it engages switch arm 35 will not actuate the bridging member 37 out of engagement with the fingers 33. Therefore when the shoes 46 are engaged by the conductor bars 47, the actuating coil for the upper section of the reversing switch 50 will be energized and a motor circuit established causing the rotation of the motor armature in the proper direction to effect a lengthening of the hanger through the operation of the buckle 20.

If the elevator car moves downwardly while the motor 39 is running, the circuit will be interrupted when the shoe 49 releases the switch 48 and interrupts the actuating circuit of the line switch 51.

If there is any arcing as a result of this interruption, it is taken by the line switch 51.

The length of the measuring stick 25 and the setting of the cam 40 will depend on the level at which the hangers deliver the truck 8. Adjustments may be effected by rotating the cam disk 40.

The throw of the switch arm 35 will depend upon the space between the collars 61 on the measuring stick 25 and the bracket 62 which extends to the right from the bracket 41 and the distance between the switch frame and the nuts on the eye-bolt 63 which carries the spring 38. The throw of the switch arm may be adjusted to meet operating conditions.

Since certain changes may be made in the above construction, and different embodiments of the invention may be made without departing from the scope thereof, it is intended that all matter contained in the above description, or shown in the accompanying drawings, shall be interpreted as illustrative and not in a limiting sense.

I claim:

1. A compensating device for apparatus provided with members which change in size with changes in temperature, comprising means for adjusting a member in accordance with its change in size to set a predetermined part in the same relation to other parts of the apparatus when a change in size takes place, and means responsive to changes in size of the member for initiating an adjusting operation.

2. A compensating device for apparatus provided with members which change in size with changes in temperature, comprising means for adjusting the member relative to the remaining members of the apparatus to set a predetermined part in the proper relation to the other parts of the apparatus each time there has been a change in size, and a measuring device for measuring the size of the member subjected to changes in temperature for initiating an adjusting operation when there has been a change in size.

3. A compensating device for hoisting apparatus provided with a depending hanger for transferring articles from one level to another in atmospheres at different temperatures, comprising means for adjusting the depending hanger when there has been a change in length resulting from changes in temperature to provide for the delivery of the articles at a predetermined level, and means responsive to changes in length of the hanger for initiating an operation of the adjusting means.

4. A compensating device for hoisting apparatus provided with members subject to changes in size with changes in temperature for transferring articles from one level to another, comprising means for adjusting said members when there has been a change in size to provide for delivering the articles at a predetermined level, a measuring device for measuring the size of the member subjected to changes in temperature, and means disposed to be actuated by said measuring device for initiating the operation of said adjusting means.

5. A compensating device for hoisting apparatus which operates in atmospheres at different temperatures, comprising means for adjusting the hoisting apparatus to a predetermined size when there has been a change from that size as a result of changes in temperature, and means automatically operable upon a change in size of the hoisting apparatus to initiate the operation of the adjusting means.

6. A compensating device for hoisting appa-

- ratus provided with a depending hanger for transferring articles from one level to another in atmospheres of different temperatures, comprising means for adjusting the hanger to a predetermined length to deliver the articles at the same level all the time, means for measuring the hanger as it approaches the level at which the articles are to be delivered, and means disposed to be actuated by the measuring means for initiating the operation of the adjusting means.
7. A compensating device for hoisting apparatus provided with a depending hanger for delivering articles at a predetermined level, comprising means for varying the length of the hanger, a motor for driving said means for varying the length of the hanger, means for measuring the length of the hanger, and means disposed to be actuated by said measuring means when the hanger is too short or too long for initiating the operation of the motor to effect adjustment of the hanger to a predetermined length.
8. In a compensating device for hoisting apparatus provided with hangers for transferring articles from one level to another in atmospheres of different temperatures, in combination, means for measuring the length of the hanger, means for adjusting the length of the hanger, and means disposed to be actuated by the measuring means when the hanger is too short or too long for initiating the operation of the adjusting means.
9. A compensating device for apparatus provided with depending hangers for transferring articles through atmospheres at different temperatures to a predetermined level, comprising means for lengthening or shortening the hanger, means for measuring the length of the hanger, a motor for driving the means for lengthening or shortening the hanger, and means carried by the measuring means for initiating the operation of the motor in either direction depending on whether the hanger should be lengthened or shortened.
10. A compensating device for hoisting apparatus provided with a depending hanger for transferring articles from one level to another through atmospheres at different temperatures, means for lengthening or shortening the hanger to adjust it to a predetermined length when it has been distorted by the temperatures, means for measuring the length of the hanger, said measuring means being substantially unresponsive to changes in temperature within the range to which it may be heated by the hanger, means for adjusting the measuring means to measure any predetermined length, and means disposed to be actuated by the measuring means to initiate a change in length of the hanger.
11. A compensating device for hoisting apparatus provided with a hanger for transferring articles through atmospheres at different temperatures and delivering them at a predetermined level, comprising means for varying the length of the hanger, a measuring stick of material substantially unaffected by the range of temperature to which it is subjected, said measuring stick being the length it is desired to maintain the hanger and disposed to be in parallel relation with the hanger when it is moving to a predetermined level at which it is to receive or deliver articles, and means disposed to be actuated by the measuring stick if it and the hanger are not of the same length to initiate the operation of the means for varying the length of the hanger.
12. A compensating device for apparatus provided with members which change in size with changes in temperature, comprising means for adjusting the member that changes in size, a measuring member which is substantially unaffected by the changes in temperature, said measuring member being disposed for movement by the member which changes in size, the movement of said measuring member depending on the size of the variable member, and means disposed to be actuated by the measuring member for adjusting said variable member.
13. A compensating device for apparatus provided with members which change in size with changes in temperature, comprising means for adjusting the member which varies in size with changes in temperature, means disposed to move the said member and in fixed relation to its connection to the apparatus, measuring means actuated by the member which varies in size, the movement of the measuring means depending on the size of the variable member, and means for actuating the adjusting means, the operation of said actuating means depending on the relative positions between the member fixed relative to the connection of the variable means and the measuring means.
14. In combination, a plurality of horizontal conveyors disposed at different levels, an elevator for transferring articles from one conveyor level to another, a heating chamber disposed in the path of the articles, said elevator having parts exposed to heating in said chamber, and means for compensating for expansion or contraction of said elevator parts upon heating or cooling to maintain accurate registry of the elevator with a conveyor.
15. In combination, a plurality of horizontal conveyors disposed at different levels and adapted to convey articles through heat treating chambers, an elevator for transferring articles from one conveyor level to another and having parts subjected to varying temperature effects, and means for compensating for changes in size of said elevator parts upon heating or cooling to maintain accurate registry of the elevator with a conveyor.

OTTO E. UECKER.
